UNITED STATES PATENT OFFICE.

ERASTUS E. WINKLEY, OF LYNN, MASSACHUSETTS, ASSIGNOR OF ONE-HALF
TO BENJAMIN PHILLIPS, OF SAME PLACE.

SOLE-PRESSING MACHINE.

SPECIFICATION forming part of Letters Patent No. 627,034, dated June 13, 1899.

Application filed July 20, 1898. Serial No. 686,410. (No model.)

To all whom it may concern:

Be it known that I, ERASTUS E. WINKLEY, a citizen of the United States, residing at Lynn, in the county of Essex and State of Massachusetts, have invented certain new and useful Improvements in Sole-Pressing Machines; and I do hereby declare the following to be a full, clear, and exact description of the invention, such as will enable others skilled in the art to which it appertains to make and use the same.

The present invention relates generally to improvements in sole-pressing machines, including machines adapted to temporarily attach the outsole to the lasted upper and insole, commonly called "sole-laying machines," and machines adapted to operate upon the outsole after it has been permanently attached to the lasted upper and insole or welt, commonly termed "sole-leveling machines."

The present invention consists of improved means for adjusting the pressure mechanism for different heights of last or thickness of sole, whereby such adjustment is effected automatically and the required pressure secured, where the above conditions vary, without manual interference on the part of the operator.

The present invention consists, further, of improved means of presenting the jacks to the forms and of other improvements in the construction and organization of the machine and the several mechanisms embodied therein, as more fully hereinafter pointed out in this specification and defined in the claims.

The accompanying drawings illustrate my invention as applied to a sole-laying machine.

Figure 1 shows the machine in side elevation; Fig. 2, in sectional elevation, portions of frame and pressure-securing mechanism being removed; Fig. 3, in front elevation, Fig. 4 illustrating details of construction of start-and-stop mechanism and Fig. 5 showing the machine in top plan.

In the several views of the drawings I have indicated like parts by like letters of reference.

In the machine illustrated, F is a frame suitable to support the working parts, hereinafter described.

A A represent a pair of shoe-supporting

jacks conveniently provided with the usual toe-rest a and heel-support a'. The jack, however, in itself forms no part of the present invention, the specific form shown being well known in the prior art and requiring no further description herein.

The forms are shown at B B and may be of any suitable construction. In practice I have found it desirable to use a form substantially similar in construction of its essential features to that shown and described in United States Letters Patent issued to me March 23, 1897, No. 579,206; but good results can be obtained with many other constructions of forms well known in the prior art. It may be stated in this connection that when the machine is to be used as a sole-leveling machine for many classes of work I prefer to use the usual metallic form instead of the rubber form of said patent and to substitute for the illustrated jacks the common iron last such as is now generally used with leveling-machines of the direct-pressure type. For leveling turn-shoes, however, while preferring to use a metallic form, I find it desirable to retain the illustrated jack or to use some other suitable device to support the wooden last, so that the leveling operation can be performed upon the wooden last upon which the shoes are lasted. This is also a desirable feature in beating out welted shoes and is made practical in my present machine by my improved means for adjusting the pressure mechanism, which prevents undue pressure where the thickness of sole and height of last varies, which is otherwise liable to break the last.

To present the jacks to the forms and to bring them into a convenient position for the adjustment of a shoe thereon or its removal therefrom, I have provided in the machine of the drawings the following mechanism, which as to certain features I consider to be novel and I will therefore describe in detail.

The jacks A A are mounted upon a jack-carrier D, which, as shown, consists of a plate or bar of suitable length, adjacent to opposite ends of which the jacks are mounted. The jack-carrier D is supported by a table d², the upper surface of which is substantially horizontal, the jack-carrier D sliding along the same when turned into and out of position,

as hereinafter described. From the center of the jack-carrier D is projected an arm or offset d , which is free to turn about a suitable bearing d' in the table d^2 or a forwardly-projected extension thereof. The bearing d' is located immediately in front of a point midway between the two jacks A A, and the distance from the center of the bearing d' to the medial line of the jacks is half the distance 10 between the forms B B. When the forms B B are arranged, as shown, with their toe ends away from the operator and their medial lines substantially parallel, the jacks A A are arranged upon the carrier D substantially in 15 line and with their heel-supports a' adjacent to each other. (See Fig. 1.) On the table d^2 are provided suitable stops d^{20} , so positioned that when the carrier D is turned against the same one of the jacks A is in proper position 20 to coöperate with its form.

The pressure mechanism of the machine of the drawings is described as follows: The table d^2 is free to reciprocate vertically along suitable vertical guides d^3 , arranged to guide 25 and laterally support the same. Upon the lower side of the table d^2 is fulcrumed the upper member of the toggle-lever d^4 , the lower member of which is fulcrumed upon the vertically-movable cross-head d^5 , which is also 30 movable along the guides d^3 . Upon the cross-head d^5 are formed two guides or bearings d^6 , which receive the vertical rods d^7 and through which said rods are free to reciprocate, being guided and held in position thereby. The 35 rods d^7 below the cross-head d^5 carry a cross-head d^8 , between which and the cross-head d^5 is interposed a coiled spring d^9 , the lower end of which bears upon the cross-head d^5 and the upper end upon a disk d^{10} , upon which 40 bears a bolt d^{11} , having a threaded bearing in the cross-head d^5 . By raising or lowering the bolt d^{11} the initial compression of the spring d^9 may be regulated. By "initial compression," as I have used the term above, I desire to be 45 understood as meaning the extent of compression of the spring before any compressing action between the jacks and forms occurs, it of course being understood that variations in such initial compression effect proportionate variations in the force required to further 50 compress the spring d^9 when the jacks A are under pressure and make their compressing action more or less resilient or yielding. The rods d^7 are capped above the guides or bearings d^6 to prevent them being drawn out when 55 the head d^5 is raised.

The cross-head d^5 when the jacks A are under pressure is arranged to bear upon an adjustable rest or stop d^{12} , (see Fig. 2,) which, 60 as shown, consists of a suitable bolt having a threaded bearing in a fixed head d^{14} , secured to the frame F, and which by means of the hand-wheel d^{15} may be raised or lowered by rotation in said bearings. Stops 65 d^{16} are provided, (see dotted lines, Fig. 3,) secured in the guides d^3 , which limit the downward movement of the table d^2 . The above-

described arrangement is such that when the table d^2 rests upon the stops d^{16} and the toggle d^4 is straightened the cross-head d^5 will move downward until the cross-head d^5 contacts with the stop or rest d^{12} , when the resistance of the spring d^9 will oppose further downward movement of the cross-head d^5 , and the table d^2 will therefore be raised, and if one of the forms B has been properly seated the jacks and forms will be brought into their position of pressure. It will be noted from the above that the function of the adjustable stop d^{12} is to regulate the amount of pressure 80 secured, which is greater or less as the cross-head d^5 contacts with the stop d^{12} earlier or later in its downward movement.

The mechanism for operating the toggle-lever d^4 is of the usual type, and a brief description thereof will be sufficient herein.

The driving-shaft of the machine is shown at E and rotates the main shaft E' by means of the gear connections e and e'. The shaft E' carries a suitably-timed cam e², which by 90 means of the connecting-link e³ operates the toggle d^4 . As shown, the link e³ is pivotally connected with the toggle d^4 at its central joint or knuckle and is slotted to receive the shaft.

In the machine of the drawings the pressure mechanism includes the forms B, the jacks A, and the mechanism for raising and lowering the jacks, as above described. The movement of the forms which I will now describe is not a movement of pressure, but an adjustment whereby the pressure mechanism prior to its pressure movement is adjusted for the height of last and thickness of sole to be operated upon. In other words, by the 105 movement of the forms the pressure mechanism is adjusted to exert on shoes of different heights of last or thickness of sole a substantially uniform pressure, the resiliency of which is regulated by the bolt d^{11} and the 110 amount of which is determined by the position of the stop d^{12} .

The forms B B are mounted upon a vertically-reciprocating head b free to reciprocate along suitable vertical guides b' in the frame. 115 To the head b is secured a vertical rod b², (see Fig. 2,) which is projected through a bearing b³ on the frame F, in which it is free to reciprocate, being guided and held in position thereby. To the rod b² is secured a vertical 120 rack b⁴, with which meshes a segmental gear b⁵, carried upon one arm of a bell-lever b⁶, which is fulcrumed at its angle upon the frame F, and the other arm of which carries a roll b⁷, arranged to be engaged by a periphery cam 125 b⁸, carried by the shaft E'. The cam b⁸ is so timed and arranged that when the machine is started with the jacks and forms in a position of pressure after the toggle has released and the head b has been unlocked, as hereinafter described, the cam b⁸ will engage the roll b⁷ and raise the head b to bring the forms B into 130 their position of clearance, and when the machine is started from a position of clearance

the cam b^8 will allow the head b to fall by its own weight until one of the forms B is seated upon the sole of a shoe upon one of the jacks A.

5 The mechanism for locking the forms B to withstand the upward pressure of the jacks after a form has been seated upon the shoe is described as follows: Above the head b , mounted in suitable bearings in the frame F, 10 is a shaft c , which carries the cams $c' c'$. The shaft c also carries a segmental gear c^2 , which meshes with a segmental gear c^3 , carried by the swinging lever c^4 , fulcrumed at c^5 on the frame F. The swinging lever c^4 carries below its fulcrum a cam-roll c^6 , which is arranged to be engaged by a periphery cam c^7 on the shaft E'. Around the shaft c is arranged a coiled spring c^8 ; one end of which engages one of the cams c' and the other end a fixed 15 portion of the frame F, so that the resilient action of said spring tends to rotate the shaft c to turn the cams c' in a forward direction. The cams c' are so formed that when turned in a forward direction they will contact with 20 the head b or a suitable bearing-block b^{15} thereon and lock the forms against upward movement. The cam c^7 is so timed and arranged that as the pressure is released it will engage the cam-roll c^6 and by means of lever 25 c^4 rotate the shaft c to turn the cams c' in rearward direction to cause them to release the head b and to allow it to be raised by the cam b^8 and its connections. After a form is seated 30 upon a shoe the cam c^7 leaves the roll c^6 and allows the spring c^8 to impart a forward rotation to the shaft c , which turns the cams c' forward until they bind upon the bearing-block b^{15} , when the forward rotation of shaft c ceases and the head b is locked from upward 35 movement by the cams c' . It will be noted that the releasing movement of cams c' is positive, while their locking movement is spring-controlled, so that it automatically varies in extent to provide for different elevations of 40 the head b , caused by differences in the height of the last or thickness of sole of the shoe upon which the working form rests.

In connection with the mechanism heretofore described I have provided in the machine 45 of the drawings a suitable start-and-stop mechanism, which is arranged to stop the machine when the jacks and forms are in their position of pressure and also when they are in a position of clearance, so that the jack 50 carrying the shoe which has been operated upon can be thrown out and the other jack brought under the form which co-operates therewith.

The start-and-stop mechanism illustrated 55 consists of pulley e^4 , which normally turns loosely upon the driving-shaft E and is free to have a limited sliding motion along the same. The pulley e^4 is locked to shaft E to rotate therewith by means of a clutch e^5 , one 60 member of which turns with the pulley e^4 , being conveniently formed upon the hub thereof, and the other member is keyed or other-

wise secured to rotate with shaft E. In the hub of the pulley e^4 is formed a circular groove e^6 , which is engaged by a segmental flange e^7 , 70 formed upon a hub carried by the shaft e^8 . The shaft e^8 is mounted to slide longitudinally and rotate in suitable bearings in frame F.

The gear e' carries two projections or dogs e^9 , (only one shown,) which are arranged as 75 the gear e' is rotated to engage a dog e^{10} on the shaft e^8 and to slide said shaft in its bearings sufficiently to disengage the members of the clutch e^5 and allow the pulley e^4 to turn loosely upon the shaft E. A treadle e^{12} is provided, which is connected with the shaft e^8 80 by means of a rod e^{20} , which connects with an arm e^{21} , secured to the shaft e^8 , whereby the shaft e^8 may be rotated to turn the dog e^{10} out of the path of the dog e^9 and to permit the 85 spring e^{14} , surrounding the shaft e^8 , to slide the shaft e^8 in its bearings to close the clutch e^5 . The shaft e^8 is rotated in an opposite direction to restore the dog e^{10} to its original position by means of a spring e^{22} , which connects 90 the arm e^{21} with a fixed portion of the frame F.

It is perhaps unnecessary to add that the stop mechanism above described forms no essential part of the present invention, as there are many forms of such mechanism in the prior 95 art whereby equally good results could be secured.

The forms B, as shown, are removably and adjustably secured to the head b , as is usual in this class of machines.

The operation of the machine of the drawings is as follows: Assuming that the jacks and forms are in their position of clearance, the operator adjusts a shoe upon one of the jacks and, having by means of the bolt d^{11} 105 and the adjustable stop d^{12} adjusted the pressure mechanism to secure the desired resiliency and pressure, turns the jack-carrier D until it contacts with the stop d^{20} , which brings the jack A under its co-operating form B. The operator then starts the machine by means of the treadle e^{12} , and the head b drops by its 110 own weight until the form B rests upon the sole of the shoe, which has been placed on the jack A. The seating of the form, as above 115 stated, stops any further downward motion of the head b , and the cams c' are thrown forward and lock it in its seated position against upward movement. After the form B has been seated and locked, as above stated, the 120 toggle d^4 is straightened and raises the table d^2 and with it the jack-carrier D and jacks A, the jack A which is under the form B being brought into a position of pressure and the sole of the shoe thereon being compressed 125 between the jack and form. At this time the jack A at the other end of carrier D is out from under the forms B and in a convenient position for the removal of a shoe therefrom or the adjustment of a shoe thereon, and the 130 machine is automatically stopped. As soon as the operator has adjusted a shoe upon the empty jack he again starts the machine, and the toggle thereupon releases the table d^2 to

relax the pressure, the cams c' are turned back to unlock the forms B, and said forms are raised until the jacks and forms are in their position of clearance, when the machine again stops. The operator then turns the carrier D until it contacts with the other stop d^{20} , which bring the jack which has just received its shoe under its coöperating form and the jack with the shoe last operated on into a convenient position for removal of a shoe therefrom, and the operator after adjusting a shoe in the empty jack again repeats the operation hereinbefore described.

I desire to say that I am aware that it has heretofore been proposed in sole-leveling machines to mount the jacks on a rotary carrier; but such carrier has never before, in so far as I am advised of the state of the art, been set off from its center of rotation, and it has heretofore been necessary where the jacks were brought in front of the machine to rotate the jacks upon the carrier in order that they might be properly presented to the forms and the operation.

By setting off the carrier from its rotation, as hereinbefore described, while presenting the jack successively at the front of the machine, I avoid this necessity of turning the jacks themselves, thereby greatly increasing the speed and efficiency of the machine.

In a prior patent issued to me April 7, 1896, No. 557,744, I have shown a sole-laying machine having provision for an adjustment of the pressure mechanism for lasts of different heights and soles of different thickness and have broadly claimed the same. It is to be noted that the mechanism of said patented machine differs from that of my present machine as to this feature, in that in said patented machine the seating movement of form is continued for the pressure movement and the seating mechanism for the form is in operative connection with the pressure mechanism, said seating mechanism acting to shift or vary the point of connection between the form and the pressure mechanism. In the present invention the seating movement of the form is entirely independent of the movement which produces pressure, and there is no connection between the form and pressure securing mechanism.

Having thus described my invention, I claim as novel and desire to secure by Letters Patent of the United States—

1. In a sole-pressing machine, the combination with a jack and form, of independent mechanisms operating automatically and successively to seat the form and to bring the form and jack into a position of pressure, substantially as described. 55

2. In a sole-pressing machine, the combination with a form member and a jack member, of mechanism to relatively actuate said members to seat the form member, automatic means to lock one of said members, and mechanism to actuate the other member to secure pressure, substantially as described. 60

3. In a sole-pressing machine, the combination with a pair of pressing-forms, of a jack-carrier having its center of rotation in front of a point between the forms, and a pair of jacks mounted on the carrier and set off from its center of rotation, substantially as described. 70

4. In a sole-pressing machine; the combination with complementary pressing members, of means to impart to one of said members a movement toward the other member to cause both members to engage the sole, means to lock one of the pressing members 80 against a return movement, and independent mechanism to move the other pressing member toward the member which is locked to press and shape the sole, substantially as described. 75

5. In a sole-pressing machine, the combination with a sole-pressing form and shoe-supporting jack, of means to move the form toward the jack to place the form in contact with the sole of the shoe, means to lock the form from movement in the reverse direction, and independent mechanism to move the jack toward the form while the form is locked, to apply pressure to the sole, substantially as described. 85

6. In a sole-pressing machine, the combination with a pair of pressing-forms, of a jack-carrier carrying a pair of jacks arranged in longitudinal alinement with each other, the said carrier being pivotally supported to turn about a center at one side of the jacks, substantially as described. 95

In testimony whereof I affix my signature in presence of two witnesses.

ERASTUS E. WINKLEY.
